UNITED STATES PATENT OFFICE.

ANTONIO SANANDRES, OF NEW YORK, N. Y.

ACOUSTIC OPTICAL TELEGRAPH.

1,025,427

Specification of Letters Patent.

Patented May 7, 1912.

Application filed May 1, 1911. Serial No. 624,298.

To all whom it may concern:

Be it known that I, ANTONIO SANANDRES, a subject of the King of Italy, residing in New York, county and State of New York, have invented certain new and useful Improvements in Acoustic Optical Telegraphs, of which the following is a specification.

This invention relates to telegraph instruments and particularly to receiving instruments of the class specified in which the indication is made both audibly and visually.

The object of my improvements is to provide such a receiving instrument whereby the message transmitted in the usual dot and dash characters is delivered in one or more visual representations wherein the dots and dashes are distinguishable from each other respectively not only by the varying duration of such visual representation but also by the varying character thereof.

To these ends my improvements comprise means described and claimed in this specification and illustrated in the accompanying drawings.

Figure 1 is a plan view with the case partly in section, of an instrument embodying the preferred form of my improvements and Fig. 2 is a similar sectional elevation of the same. Figs. 3 and 4 are diagrammatic plan views illustrating the operation of my improved device.

The illustrated instrument comprises the usual coil magnet 3, 3 and armature 4 for engagement therewith. Said armature is fixed to cross arm 7 pivoted at 5, 5 in uprights 6, 6, respectively and has its rearwardly reaching arm 12 bearing upon stop 8 fixed to the rear wall 9 of the case. A spring 10 tending to hold armature 4 out of contact with magnet 3, 3 is connected by one end to arm 7 and by the other end to base 11 on which said magnet is fixed. Standing from cross arm 7 is bracket 21 having fixed thereto reflector 22 visible through opening 23 in front 24 of said case. I employ reflector 22 in preference to a non-reflecting indicator so that a ray of light may be cast thereon from some convenient source, not shown, and thus increase the brilliance of the optical indication. Table top 25 of said case is provided with a slot or perforation 13 therethrough. Directly below said table top 25 an indicator or pointer 14 is mounted for movement relative to said slot 13. Said indicator is

preferably of triangular shape and one of its angles or points as 15 is located directly below slot 13 or just rearwardly thereof, so that a slight forward movement, away from the magnet as illustrated, will bring said point 15 into view, and a greater movement thereof will bring a wider portion of its face into view, the point corresponding with the dot of the Morse telegraphic characters and the wider portion with a dash thereof. Said indicator 14 is mounted for movement in approximately the plane of table top 25, by some suitable means as thin springs, 16, 16 fixed at their upper ends to the underside of said indicator and at their lower ends to base 17 of said case. Depending from armature cross arm 7 is rod 18 the lower end of which is guided for vertical movement in foot 19 fixed to base 17. Below table top 25 and fixed to rod 18 is wedge 20 for engagement with yieldable spring arm 26 fixed to indicator 14.

The operation of my improved instrument is as follows:—Magnet 3, 3 having been energized by an electric current from a sending instrument in the usual well known manner, armature 4 fixed to the free end of cross arm 7 is drawn down into contact with said magnet thereby making the usual contact sound and reflector 22 moves downwardly and slightly forwardly behind opening 23 and which movement is clearly visible through said opening. The duration of contact of said armature and magnet and the duration of said reflector's remaining in its downward position indicate audibly and visually respectively, whether a dot or dash is transmitted. At the same time, rod 18 and wedge 20 are moved downwardly and said wedge engages arm 26 of indicator 14 thereby moving said indicator forwardly under and into view through slot 13, one or both edges of which slot serve as a gage against which to read the movement of said indicator. If said wedge 20 remains in its downward position only an instant, Fig. 3, the inertia of indicator 14 will be only partially overcome and spring arm 26 will yield toward said indicator. The forward movement of said indicator will therefore be slight and a dot will be indicated. On the other hand if said wedge 20 remains in its downward position a longer time the inertia of indicator 14 will be more fully overcome by the recoil of spring arm 26 and said indicator will be moved forwardly a greater dis-

tance, Fig. 4, thereby exposing a broader portion through slot 13, indicating a dash. The circuit then being broken the parts return to their idle positions as shown in Figs. 1 and 2. If spring arm 26 is relatively rigid, right hand spring 16, Fig. 2, will tend to collapse under the initial downward movement of wedge 20, thus indicating a dot. If wedge 20 is held down for a longer period 10 arm 26 will slide upwardly on wedge 20 and indicator 14 will be advanced as shown in Fig. 4. As the speed of armature 7 in its movement toward magnet 3, 3 is governed entirely by the electric current which energizes said magnet and which current is substantially constant, said speed of movement will remain constant no matter how rapidly the circuit is made and broken. It will thus be seen that a dot or dash indication will 15 20 be given by indicator 14 in accordance with the length of time wedge 20 remains in its downward position.

I claim:

1. A telegraph instrument including in combination, a magnet, an armature mounted for movement toward and from said magnet, a gage, an indicator having a face increasing in width as it recedes from said gage and means for moving said indicator 25 30 from said armature to expose a narrow portion thereof for a dot impulse and a wider portion for a dash impulse.

2. A telegraph instrument including in combination, a magnet, an armature mounted for movement toward and from said magnet, a table having a slot therein, an indicator below said table and mounted for movement into and out of view through said slot and means for moving said indicator 35 40 from said armature, distances varying with the duration of contact of said armature and magnet.

3. A telegraph instrument including in combination, a magnet, an armature pivotally mounted for movement toward and from said magnet, a reflector fixed to said armature, a gage, an indicator mounted for movement relative to said gage and means 45

for moving said indicator from said armature, distances varying with the duration of contact of said armature and magnet.

4. A telegraph instrument including in combination, a magnet, an armature pivotally mounted for movement toward and from said magnet, a reflector fixed to said armature, a table having a slot therein, a tapered indicator below said table and mounted for movement into and out of view through said slot and means for moving said indicator from said armature to expose a narrow portion thereof for a dot impulse and a wider portion for a dash impulse.

5. A telegraph instrument including in combination, a magnet, an armature mounted for movement toward and from said magnet, a gage, an indicator mounted for movement relative to said gage and means for moving said indicator from said armature distances varying with the duration of contact of said armature and magnet.

6. A telegraph instrument including in combination, a magnet, an armature mounted for movement toward and from said magnet, a gage, an indicator mounted for movement relative to said gage, a yieldable arm fixed to said indicator and means for moving said indicator through said arm from said armature.

7. A telegraph instrument including in combination, a magnet, an armature mounted for movement toward and from said magnet, a table having a slot therein, an indicator below said table and mounted for movement into and out of view through said slot, a yieldable arm fixed to said indicator and means for moving said arm from said armature to transmit movement to said indicator varied in distance by the duration of contact of said armature and magnet.

Signed at New York, N. Y. this 29th day of April 1911 before two subscribing witnesses.

ANTONIO SANANDRES.
